UNITED STATES PATENT OFFICE.

EDWIN E. CARLSON, OF CHESTER, PENNSYLVANIA.

MACHINE FOR UNWINDING WARP SHEETS.

Application filed February 5, 1925. Serial No. 6,979.

To all whom it may concern:

Be it known that I, EDWIN E. CARLSON, a citizen of the United States, residing at Chester, in the county of Delaware and State 5 of Pennsylvania, have invented certain new and useful Improvements in Machines for Unwinding Warp Sheets, of which the following is a specification.

My invention relates to unwinding machines and is primarily designed for use in unwinding the binding thread of the warp sheet which passes through the solutions employed for mercerizing yarns.

In mercerizing yarns, strands of yarn 15 have usually been grouped in rope form and a number of groups concurrently led through the mercerizing solution. A binding thread is wound spirally about each group to hold loose ends of threads which 20 may be broken in the mercerizing process to their group and prevent their clinging to and being wound around the rollers in the mercerizing mechanism. After the mercerizing is completed, the binding thread must 25 be removed to permit separation of the strands composing each group, and a separate unwinding machine is provided for each group. It is common practice to pass 16 groups through the mercerizing unit at 30 one operation and this involves providing 16 unwinding machines. It has recently been found advantageous to group the strands side by side in single ply thereby forming a single warp sheet and to bind 35 the entire warp sheet with a single thread instead of binding each group separately. I have designed a machine adapted for winding the warp sheet which is disclosed in Patent No. 1,554,557.

40 The winding machine, by reversing its motion, functions as an unwinding machine but to attain the best results in unwinding, some additional features and some modification of other features are highly desirable, if 45 not essential, and the object of this invention is to provide mechanism especially adapted for unwinding warp sheets or other continuous sheets.

In the drawings,

- 50 Figure 1 is a top plan view,
Figure 2 a side elevation,
Figure 3 a section on line 3—3 of Figure 2,
Figure 4 a section on line 4—4 of Figure 2,
Figure 5 a fragmentary top plan view
55 showing on an enlarged scale part of the mechanism shown in Figure 2,

Figure 6 a fragmentary side elevation showing on an enlarged scale part of the mechanism shown in Figure 2,

Figure 7 a vertical section through the 60 spool-carrier and spool,

Figure 8 a section on line 8—8 of Figure 6, and

Figure 9 an enlarged detail of a reversing 65 screw.

In the drawings, 1 indicates the frame of the machine, 2 the top or table, 3 cross bars, 4 a guide slot in the table through which the warp is led, 5 an oblong raceway of slot type encompassing the warp and having guide walls 6 and 7 within and upon which a spool carrier 8 travels, 9 a drive sprocket and 10 a companion sprocket both disposed beneath the raceway, 11 a sprocket chain carried by the sprockets, encompassing the warp and having one of its links 12 detachably connected with a bearing block 13 adapted to support a spool-carrying spindle 14, 15 a sprocket chain spaced from chain 11, disposed parallel thereto and detachably fixed to a series of brackets 16 extending from the frame, 17 a sprocket wheel fixed to the spool spindle and meshing with chain 15, 18 a reversing screw disposed parallel to the spool and rotatably mounted on a bracket 20 fixed to the spool carrier, 21 a star wheel fixed to the reversing screw and adapted to engage with pins 22 extending upwardly from the frame, adjacent the outer periphery of the raceway, and to be 70 rotated thereby, and 23 the spool upon which the thread is to be wound. The spool is rotatable upon its spindle 14 and is mounted upon spool-carrier 8. The spool-carrier, shown in detail in Figure 7, preferably consists of a sleeve 24 having an annular flange 25 and an enlarged part 26 and threaded at its outer end to receive a step ball bearing 27 having annular flanges 28 and 29. The lower member of the ball bearing is splined to the spindle and rotatable therewith. The upper member carries a friction disk 30 upon which spool 23 is seated. The lower flange 28 supports the carrier upon the guide walls 6 and 7 of the raceway and flange 25 holds the carrier against upward displacement. Enlarged part 26 fits in the raceway slot and serves as a guide block for the spool-carrier. It preferably has a straight inner 80 face and an outer face curved to correspond with the arc of the end parts of the raceway, as indicated by dotted lines in Figure 90

5, to provide a maximum of bearing face. A thread guide 31, shown in detail in Figure 8, is mounted to slide upon a guide rod 32 carried by bracket 20 and upon reversing screw 18. A follower 33 seated in a socket 34 has a head 35 adapted to travel in the threads of the screw. As the screw is cross threaded its rotation will cause the follower and consequently the thread guide to travel 10 alternately upward and downward thereby causing the thread to be wound evenly in successive layers. The guide carries a fixed hook shaped member 36 and a fixed pin 37. A rock shaft 38 is mounted in suitable bearings in the guide and has a block 39 fixed thereto, rockably seated in a socket 40 between hooked member 36 and fixed pin 37. A pin 41 extends from the block in a plane between members 36 and 37. The binding 20 thread 42, as it comes from the warp sheet, passes through the hook of member 36, over pin 41, under pin 37 and then to spool 23. Rock shaft 38 has a crank arm 43 fixed to one of its ends and carrying an electrical 25 contact 44 adapted to engage a fixed contact 45 on the thread guide. Brushes 46 and 47 are mounted upon the spool carrier and are connected by wires 48 and 49 with contact members 44 and 45 on the thread 30 guide. The brushes are adapted to respectively engage conducting strips 50 and 51 mounted upon insulating brackets 52 extending from the frame 1. Conducting strips 50 and 51 are in circuit, through a 35 source of current 53 and a solenoid switch 54, which controls the motor 55, and contact of members 44 and 45 closes the normally open circuit and stops the motor.

The tension of the binding thread taking 40 over pin 41 normally holds contact 44 out of engagement but, if the thread should break, the weight of crank arm 43 rocks shaft 38 and contact 44 engages contact 45 and closes the circuit through the solenoid 45 switch and stops the motor.

Drive sprocket 9 is mounted upon a shaft 57. A drive shaft 58 carries a spiral pinion 59 which meshes with a spiral gear 60 on shaft 57 and imparts motion to the shaft 50 and consequently to the drive sprocket and the movable chain.

In operation the binding thread which has 55 been wrapped spirally about the warp sheet leads through hook-shaped member 36 over pin 41 and under pin 37 on thread guide 31 to spool 23 with which it is connected. Motion being imparted to drive sprocket 9 from drive shaft 58, sprocket chain 11 to which spool carrier 8 is connected, is caused to travel continuously around the warp sheet thereby causing the spool carrier to travel, in raceway 5, around the warp sheet. As the spool travels, rotary motion is imparted to its spindle 14 by sprocket wheel 17 meshing 60 with fixed sprocket chain 15. As the

spool travels in the raceway, reversing screw 18, which travels with the spool, is caused to rotate by successive engagement of star wheel 21 with pins 22. Rotation of the reversing screw causes follower 33 and consequently thread guide 31 to travel alternately upwardly and downwardly alongside the spool thereby causing the binding thread to be evenly wound upon the spool in successive layers. As the spool is seated upon a friction member which is carried by a ball bearing member, the spool is free to yield to undue strains. In case the binding thread should break, crank arm 43, which has been held in raised position by the tension of the binding thread upon pin 41, drops by gravity thereby bringing electrical contact 44 into engagement with contact 45, thereby closing the circuit through the solenoid switch and stopping the motor.

While I have described my invention as taking a particular form, it will be understood that the various parts may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. In a machine for unwinding warp sheets, an endless carrier encompassing the warp sheet, a spool carrier attached thereto, a spool spindle and spool carried thereby, a reversing screw rotatably mounted on the spool carrier, a thread guide operatively connected with the reversing screw, a series of pins disposed adjacent the path of travel of the spool carrier, and a star wheel fixed to the reversing screw adapted for engagement with the pins and to be rotated thereby.

2. In a machine for unwinding warp sheets, a frame, an oblong raceway mounted on the frame and encompassing the warp sheet, an endless carrier encompassing the warp sheet, means for imparting motion thereto, an endless chain encompassing the warp sheet and fixed to the frame, a spool carrier attached thereto and adapted to travel in the raceway, a spool spindle and a spool carried thereby, a sprocket wheel fixed to the spool spindle and meshing with the fixed chain, a reversing screw rotatably mounted on the spool carrier, a thread guide operatively connected therewith, a series of pins extending from the frame adjacent the raceway and a star wheel fixed to the screw adapted to engage with the pins and to be rotated thereby.

3. In a machine for unwinding warp sheets, an endless carrier encompassing the warp sheet, a motor for imparting movement to the endless carrier, a spool carrier,

a spool spindle and spool carried thereby,
means for rotating the spool, a bracket ex-
tending from the spool carrier, a standard
extending from the bracket, a reversing
screw rotatably mounted in the bracket,
means for rotating the screw, a thread guide
slidably mounted on the standard and op-
eratively connected with the screw, a pair
of insulating conducting strips arranged ad-
10 jacent the path of travel of the spool car-
rier and in circuit with a switch controlling
the motor, a pair of brushes on the spool

carrier contacting with the conducting
strips, a fixed and a movable contact member
on the thread guide, and means on the 15
thread guide whereby tension on the thread
normally holds the movable contact mem-
ber in open position and release of tension
allows it to close and thereby close the switch
circuit and stop the motor.

20 In testimony whereof I have signed my
name to this specification.

EDWIN E. CARLSON.
